UNITED STATES PATENT OFFICE.

JOHN P. GAREY, OF ELMIRA, NEW YORK, ASSIGNOR TO ECLIPSE MACHINE COMPANY,
OF ELMIRA, NEW YORK, A CORPORATION OF NEW YORK.

SPINNING FRAME AND THE LIKE.

Application filed July 16, 1919, Serial No. 311,221. Renewed December 13, 1922.

To all whom it may concern:

Be it known that I, JOHN P. GAREY, a citizen of the United States, residing at Elmira, in the county of Chemung and State 5 of New York, have invented certain new and useful Improvements in Spinning Frames and the like, of which the following is a specification.

My invention has for its object to reduce 10 the waste of spinning fibre and injury to the machinery of the frame due to the breakage of the rovings during spinning. In spinning frames, to which my invention is particularly applicable, two or more 15 strands or rovings are drawn from a corresponding number of supply bobbins, united and passed through a set of drawing rolls by which the rovings are lengthened but reduced in body. From the last pair of drawing rolls the combined roving passes to a 20 bobbin upon a revolving spindle upon which it is wound, but first passes through a guide eye concentric with, or in the line of the axis of the spindle, and thence through a 25 traveler whereby the proper twist is given to the yarn. The individual strands or rovings and the joint roving or yarn, especially before the twist has been given to the latter in the machine, are quite irregular and weak 30 and frequently break either in the drawing rolls while undergoing the drawing operation, or after leaving the rolls and before being wound upon the bobbin. As the rolls continue to revolve after such a breakage 35 the loose end of the roving or rovings, which continues to be drawn by the drawing rolls, winds, either about one of the drawing rolls or the scavenger roll until it is discovered or perhaps becomes entangled with an adjacent roving. As each operative has under inspection a very large number of such 40 spinning units, it frequently happens that the breakage of a roving is unobserved until a considerable quantity of fibre has accumulated on the roll, damaging the other member of the pair of rolls and requiring to be removed and wasted or returned with the supply of raw material to be again reproduced. When the loose end becomes entangled with an adjacent thread the latter 45 becomes irregular and is rendered unfit for its intended use.

Numerous attempts have been made in the prior art to avoid this difficulty by the

provision of means for severing the roving 55 between the supply spools and the back pair of drawing rolls whenever the roving is broken beyond the latter. Commonly a knife, clamp, or other severing means is so arranged as to part the roving before or in 60 advance of the bite of the first pair of drawing rolls, the device, however, being normally held out of engagement as long as the roving is intact between the drawing rolls and the guide above mentioned by a 65 trigger or finger engaging the roving between the rolls and guide. As the thread or roving is rather weak and irregular any considerable pressure of the trigger or feeler against the same so greatly increases the 70 strain and friction due to the guide as to cause a great many additional breakages. For this reason devices of this character have never gone into general use in spinning machinery.

It is the purpose of my invention to provide a device of this character which will be certain and delicate in operation so as to insure the severing of the roving between the supply and the back pair of drawing 80 rolls when breakage occurs beyond that point, but which will not materially increase friction or strain upon the joint roving over that which is ordinarily due to the concentric guide alone, and will therefore not result in an increased number of breakages. It comprises a severing device maintained in normal position by a latch so poised that the breakage of the yarn alone is not sufficient to cause it to release the severing device without some impulse such as the vibration of the machine or a slight pressure such as provided by the means hereinafter described. The guide eye by which the roving or yarn is directed to the spinning mechanism proper is carried by the latch or trigger which controls the severing device and constitutes the only point of contact with the yarn between the drawing rolls and the traveler of the spinning ring, thus dispensing with one of the points of contact found in previous spinning mechanisms equipped with severing means. The pressure of the eye upon the roving is no greater than that where no severing means is employed, by 100 reason of the construction of the latch and severing means hereinafter described. Another feature of the invention of great prac-

tical importance is the manner of mounting the thread guide which facilitates doffing and also prevents the accumulation of fibres in the neighborhood of the spinning mechanism where they are apt to become entangled with the rovings and break the same or make them irregular and therefore of inferior value.

For the purpose of exemplification and illustration I have shown in the accompanying drawing and described in the following specification, preferred embodiments of my invention as applied to spinning frames of ordinary type.

It will be understood that the invention is not confined to spinning frames or to the particular form thereof shown, but it is applicable to other forms of spinning frames, drawing, twisting and doubling machinery and a great variety of mechanisms where similar conditions prevail, and therefore when reference is made to spinning machinery it is to be understood as including such equivalent or similar machines as fall within the scope of the invention as defined in the claims, in which I have endeavored to distinguish the invention from the prior art so far as known to me without, however, relinquishing or abandoning any portion or feature thereof.

In the accompanying drawings Fig. 1 is a vertical section through a spinning frame equipped with a preferred form of my invention; Fig. 2 is a fragmentary front elevation with parts removed for clearness of illustration, showing one of the severing devices and controlling mechanism; Fig. 3 is a fragmentary plan view of a detail partly in section; Fig. 4 is a plan view of a portion of the latch showing the guide; Figs. 5 and 6 are vertical sections on an enlarged scale and at right angles to each other of a detail; Fig. 7 is a vertical section similar to Fig. 1 of a second form of the invention, and Fig. 8 is a similar view of the third form.

Each part and element of the construction is identified by the same reference character wherever it is shown in the several views. Referring now to the form of the invention shown in Figs. 1 to 6 inclusive, the spinning frame may be and is shown as of an ordinary type, comprising frame members, including board 10, on which are arranged a large number of spinning units. The spinning mechanism proper comprises a spindle 11, rotated by suitable mechanism not shown, on which is mounted a spool 12 to receive the roving or completed yarn, a ring board 13 constructed and arranged to be reciprocated vertically to carry the ring 14 and traveler 15 thereon longitudinally of the spool during the winding operation. The usual drawing rolls are shown at 16, comprising three pairs of rolls 16^a, 16^b and 16^c revolved at

progressively increasing speeds so that the yarn or roving is drawn or lengthened by the relative movement of the fibres between successive pairs of rolls. Supply bobbins 17 of which there are commonly two for each set of drawing rolls and spinning mechanism, are mounted behind the drawing rolls in position to feed the rovings thereon to the bite of the rolls. Rovings 18, 19 from the respective bobbins of each set are carried through a trumpet guide 20 to the first pair of drawing rolls 16^a, thence through rolls 16^b, 16^c to a guide 21 which is mounted in the axis of rotation of the spindle 11 and from which the roving or yarn is carried through the traveler 15 and thence to the spool 12. The trumpet guide 20 is mounted upon a reciprocating slide-bar 22 which extends longitudinally of the frame and is common to all of the sets of drawing rolls and is reciprocated by suitable mechanism not shown. Except for the specific form of the thread guide 21, described hereinafter, the mechanism as thus far set forth is that which is common to most spinning machinery, and therefore need not be further set forth. A supporting bar 23 performs its usual service of supporting the bearings of the drawing rolls.

In the forms of the invention shown the severing means are gravity actuated and in the nature of clamps which grip the rovings, when released, for the purpose of holding them against the draft of the drawing rolls until they break, though, in the broader aspect of the invention, other forms of severing device may be employed. In the specific form of the invention illustrated the severing means are mounted upon brackets 24 which are clamped at suitable intervals to the aforesaid supporting rod 23, there being one of said brackets for each pair of spinning units arranged between the latter and carrying a pair of independently acting severing devices. Each bracket is secured in position by a clamp screw 25. The severing device or gripping means shown comprises a pair of combs 26, 27 secured to a back or connecting member 28, and the latter is formed or provided with a lug or extension 29 by which it is pivoted to the bracket. The bracket is formed with a pair of upwardly extending ears 30 which receive the pivot pin 31, which extends through the lugs 29 upon the severing devices. In order that the lugs may be received upon the same pin 31 they are somewhat offset with respect to each other, as best shown in Fig. 1. The combs 26, 27 on each of the severing devices are so spaced from each other that when the device falls said combs depend upon opposite sides of the supporting bar 23. As the slits 32 between the adjacent teeth are flared but taper to a width which is adapted to grip the rovings, when the device falls the rovings are

forced up into the slits, this action being assisted by the bar 23 which supports the rovings against downward movement.

The latch or trigger 33 by which the severing device is normally maintained in its raised position is pivoted at 34 and provided at one end with the guide eye 21, above mentioned, and at the other with a finger 35 which engages the severing device. The body of the latch is formed of resilient wire for a reason which will appear and provision is made for accurate adjustment in order that the eye 21 may be properly placed with reference to the spindle and the finger 35 with reference to the severing device. For this purpose the wire body 33 passes through a barrel 36, with reference to which it may be adjusted by means of the set screw 37, and said barrel is pivoted between lugs 38 on a laterally adjustable support 39 (see Figs. 5 and 6). The support 39 is mounted in a bracket 40 secured to the board 10, said bracket being provided with a groove or slot 41 to receive the support 39 and a screw 42 for clamping the support in adjusted position in the slot. By the construction just described I provide for both lateral and longitudinal adjustment of the latch body with respect to the bracket 40, the spinning mechanism, and severing device. The forward end of the latch member is laterally bent at 43 to form a pivot upon which the guide carrying end 44 is mounted. The guide eye 21 is of the usual pigtail variety and the wire from which it is formed extends rearwardly as at 45 into a sleeve 47 in which it is longitudinally adjusted by means of a set screw 48. The other end of the sleeve receives a wire 46 which passes to a bearing block 50 having at its rear end a wire 49 laterally bent as at 51 to engage beneath the wire 33. The pivot block 50 is perforated to receive the laterally bent end 43 of wire 33 and a nut 52 prevents the pivot block slipping off the end of the wire 43. Obviously the guide carrying end of the latch may be tilted with respect to the body thereof for the purpose of doffing the spindle, but while said end is free to turn upwardly upon the pivot 43, its downward movement is limited by the stop 51 engaging the body of the wire 33. The sleeve 47 permits a limited but delicate adjustment of the guide eye longitudinally of the latch.

The rear end of the latch is bent upwardly, as best shown in Fig. 1, at 53, and in its normal position is closely adjacent to or in contact with the bar 23. At the upper end of the upright portion 53 the wire is bent rearwardly as at 54 and then laterally at 55, (see Fig. 2) and upon the said lateral projection the finger 35 is adjustably mounted by means of a collar 56 and screw 57. The collar permits of lateral and angular adjust-

ment of the finger 35, so as to bring the latter to the correct position to engage the flange 58 upon the gravity actuated severing device. A counterweight 59 is adjustable upon the latch so as to very slightly overbalance the latter on the rearward side, the adjustment being such that with the severing device removed from contact with the finger 35 and the yarn broken so as to exert no pressure upon the guide eye the latch will tilt, but with the severing device bearing upon the finger 35, even when the yarn or roving is broken, the latch will maintain its operative position unless it be jarred as by the vibration of the machine or be given a slight impulse away from the severing device. In the construction shown in Figs. 1 to 6 inclusive I do not depend upon the vibration of the machine to release the latch when the roving is broken but give it a positive impulse by means of a cam 60 carried by the reciprocating trumpet guide bar 22. Because of the form and length of the cam 60 and the resilience of the wire of which the latch or trigger is composed, when the parts are in the normal position shown in Fig. 1, the cam wipes past the latch giving it a very slight impulse which is not however sufficient to overcome the pressure of the roving against the eye 21 and the friction of the finger 35 against the severing device. When, however, the roving breaks so that it no longer presents a resistance to the tilting of the latch the friction of finger 35 against the severing device not being sufficient of itself to resist the impulse given by the cam to the latch, the latter tilts to remove the finger 35 from supporting position and the severing device drops into engagement with the rovings and grips the latter. The continued rotation of the draft rollers almost immediately breaks the rovings between the combs by which it is held and the first pair of rollers. The further rotation of the draft rollers merely discharges the end of the roving thus there is no considerable amount of fiber or roving which can wind upon the rolls or engage the neighboring rovings and thereby cause trouble. When the operator perceives that the roving has broken all that is necessary for him to do is to reset the severing device, feed the component rovings through the draft rolls and splice the end of the combined roving so formed to the end of the roving or yarn upon the spool.

When the spool of any spinning unit is full it must be doffed by raising it vertically, and for this purpose, as heretofore stated, the forward end of its respective guide must be tilted out of the way and this may be readily done by reason of the pivoted construction of the tilting end 44 as heretofore described. In order that the entire latch or trigger may not be disturbed during this doffing operation I provide an

oscillatable shaft 61, parallel to and adjacent the supporting bar 23 and on the opposite side of the upright portions 53 of the latches, and said shaft is provided opposite 5 or in register with each latch with a cam 62 which normally is in the position shown in Fig. 1 in which it is out of contact with its respective latch, but when it is desired to doff the machine the shaft may be rotated 10 into a position in which the cams engage their respective latches and hold the same against movement during the manipulation of the pivoted tilting ends thereof. While the pivoted ends carrying the guide eyes 15 might be individually tilted and the spindles correspondingly doffed, it is the common practice to doff all of the spindles of a frame at the same time and with this in view I have provided means for raising the guide 20 eye carrying ends of the latches simultaneously. For this purpose an angle bar 63 extends throughout the frame beneath the wires of the guide eyes and is supported at suitable intervals on arms 64 which are 25 pivoted to brackets 65 on the frame by means of trunnions 66 mounted on said brackets. In order to raise all of the guides together therefore it is necessary merely to swing the angle bar 63 upwardly about the 30 pivots 66. After the spools have been replaced the bar 63 is swung to the normal position shown and the triggers released by oscillating the shaft 61.

The constructions shown in Figs. 7 and 8 35 are substantially like that above described except for the means for giving the respective latches or triggers the initial impulse by which, on the breakage of the roving or yarn they release the severing device. In 40 the form of the invention shown in Fig. 7 the frame 70, which is ordinarily found in machines, of this character supporting the scavenger roll 71 and pivoted as at 72 is provided along its rear bar 73 with bosses 45 74 which are arranged to engage the latches and exert a slight intermittent pressure thereon, by reason of the slight oscillation given frame 70 by the scavenger roller 71 bearing against draft roll 16". Except in 50 respect to the specific means by which the impulse is given to the latch the operation of this form of the invention is identical with that of the form heretofore described and it is therefore not necessary to describe 55 the details thereof.

In the form of the invention shown in Fig. 8 the very considerable vibration which spinning frames always have in operation is relied on to initiate the movement of any 60 latch when the corresponding roving or yarn breaks without other impulse and except in this respect the construction and operation is identical with those heretofore described.

65 Whichever form is adopted my invention

provides a severing means which operates promptly upon breakage of the thread or roving and yet which is controlled by such delicate pressure upon the thread or roving as not to substantially increase the friction 70 thereon or breakage thereof. By reason of the resilience of the thread guide mounting, referred to above, a great deal of the breakage incident to the rigidly mounted guides of the prior art is prevented. Furthermore 75 with my improved construction of thread guide the necessary slack in the thread for doffing may be had without the usual series of starting and stopping operations which frequently result in breakage of the roving 80 by reason of the sudden jerks given to the latter. As my thread guides are constructed the mere lifting thereof in the manner described provides the necessary slack for doffing. 85

I claim:

1. In a machine of the class described and in combination with the bobbin support, drawing rolls and spinning mechanism thereof, means pivoted adjacent to the drawing rolls for severing the roving, a latch engaging said severing means above the rolls for maintaining said means out of contact with the roving, and a guide on said latch intermediate the rolls and spinning 95 mechanism for directing thread to the latter.

2. In a spinning frame and in combination with the bobbin supports, drawing rolls and spinning mechanism proper thereof, roving severing means mounted on said 100 frame adjacent the rolls, a pivotal latch normally engaging said severing means above the rolls and maintaining it out of contact with the roving, a thread guide mounted on said latch and located above the 105 spinning mechanism, said guide receiving the thread directly from the rolls and guiding it directly to the spinning mechanism.

3. In a spinning frame and in combination with the feeding means and spinning 110 mechanism thereof, a severing mechanism for the rovings pivotally mounted on the frame and adapted to swing downward to sever the rovings, a latch provided with a guide for the thread intermediate the feeding means and the spinning mechanism, said latch pivoted to the frame and adapted to hold the severing mechanism in raised position when the thread is unbroken, the latch and severing means being so constructed and 115 arranged that the pressure of the latter on the former is sufficient alone to maintain co-operative relation when the machine is at rest but is insufficient therefor under the vibration of the machine when in operation. 120

4. In a machine of the class described and in combination with the feeding means pivoted and spinning mechanism thereof, means adjacent to the feeding means and moving vertically into contact with the rov- 125

- ing for severing the latter, a latch for maintaining said means out of contact with the rovings, a guide on said latch intermediate the feeding means and spinning mechanism 5 for directing the thread to the latter, and means for giving the latch a slight impulse in a direction to withdraw it from the severing means.
5. In a machine of the class described and 10 in combination with the feeding means and spinning mechanism thereof, means adjacent the feeding means for severing the rovings, a latch for maintaining said means out of contact with the rovings, said latch adapted 15 to bear upon the thread intermediate the feeding means and spinning mechanism, and means for intermittently giving said latch an impulse in a direction to release the severing means.
- 20 6. In a machine of the class described and in combination with the feeding means and spinning mechanism thereof, means adjacent to the feeding means for severing the rovings, a pivoted latch engaging the severing 25 means for maintaining it normally out of contact with the rovings, the engagement of the latch with the severing means being such that with the machine at rest the parts are maintained in normal position by such en- 30 gagement, but when the machine is operated the vibration thereof causes the latch to leave the severing means when said latch is otherwise unsupported, and said latch engaging the thread intermediate the feeding 35 means and spinning mechanism and held thereby in operative position.
7. In a spinning frame and in combination with the drawing rolls and spinning mechanism thereof, a roving severing means 40 pivoted on the frame on an axis transverse to that of the rolls, and above the bite of the latter and adapted to descend by gravity into contact with the roving, a pivoted latch normally engaging the severing means at a point 45 above the rolls and maintaining it in raised position, and a thread guide on the latch intermediate the drawing rolls and the spinning mechanism.
8. In a spinning frame and in combination 50 with the feeding means and spinning mechanism thereof, roving severing means comprising a stationary bar and a pair of parallel combs adapted to descend into contact with the roving on opposite sides of the 55 stationary bar, and a latch pivoted to the frame and normally engaging the severing means and holding it in raised position, said latch having a thread guide engaging a thread intermediate the feeding mechanism 60 and the spinning mechanism.
9. In a spinning frame and in combination 65 with the drawing rolls and spinning mechanism thereof, a support bar adjacent the rolls, roving severing means comprising a pair of combs pivoted to said bar trans- 70 versely thereof and adapted to descend upon opposite sides of the bar when released, a pivoted latch engaging said severing means and normally maintaining it out of contact with the roving, and a thread guide on said latch engaging the thread intermediate the drawing rolls and the spinning mechanism.
10. In a spinning frame and in combination 75 with the feeding and spinning mechanisms thereof, a guide for each spinning unit, a separate support for each guide projecting forwardly from the frame and to the end of which said guide is pivoted, and means for raising the guide.
11. In a spinning frame and in combination 80 with the feeding and spinning mechanisms thereof, a guide for each spinning unit, a resilient wire support for said guide extending forwardly of the frame, the guide being pivoted to the support, and means for 85 raising the guide.
12. In a spinning frame and in combination 90 with the feeding means and spinning mechanism thereof, a roving severing means adjacent the feeding mechanism, a pivoted latch, a finger adjustable relatively to said latch and engaging the severing means to maintain it in raised position, and a thread guide on said latch intermediate the feeding 95 means and spinning mechanism.
13. In a spinning frame and in combination 100 with the drawing rolls and spinning mechanism thereof, roving severing means adjacent the drawing rolls, a pivoted latch normally engaging said severing means and holding it out of contact with the roving, a thread guide pivoted to said latch and adapted to receive the thread directly from the drawing rolls and to guide it directly to the spinning mechanism, and means for rais- 105 ing said thread guide.
14. In a spinning frame and in combination 110 with the drawing rolls and spinning mechanism thereof, roving severing means adjacent the drawing rolls, a pivoted latch adapted to engage the severing means and normally maintain it out of engagement with the roving, a thread guide pivoted on said latch and engaging the thread intermediate the drawing rolls and the spinning 115 mechanism, and means pivoted to the frame and adapted to engage the thread guide and raise it out of operative position.
15. In a spinning frame and in combination 120 with the drawing rolls and spinning mechanism thereof, a latch pivoted on the frame and adapted to engage the severing means and maintain it out of engagement with the roving, a thread guide pivoted on said latch and engaging the thread intermediate the drawing rolls and the spinning mechanism, means for raising said thread guide out of operative position, and means 125 for clamping said latch against movement when the thread guide is raised.

16. In a spinning frame and in combination with the drawing rolls and spinning mechanism thereof, roving severing means adjacent each set of rolls, a pivoted latch 5 adapted to hold each roving severing means out of engagement with the rovings, a thread guide pivotally mounted upon each latch, means common to all the guides for raising the same into inoperative position, 10 and means common to all the latches for locking them in position when the thread guides are raised.
17. In a spinning frame and in combination with the drawing rolls and spinning mechanism thereof, a roving severing means for each set of drawing rolls, a support bar 15 on which all of said severing means are pivoted, a latch for each severing means pivoted on the frame and adapted to normally hold 20 its respective severing means out of engagement with the roving, a thread guide pivotally mounted on each latch, means common to all the thread guides for raising them into inoperative position, and clamping 25 means common to all the latches for locking them against the supporting bar.
18. In a spinning frame and in combination with the bobbin supports, drawing rolls and spinning mechanism thereof, a roving severing means for each set of drawing rolls comprising a roving engaging means pivoted to fall in a substantially vertical plane into contact with the roving, a latch pivoted on an axis substantially parallel to 30 the axes of the rolls and beneath the latter and normally supporting the roving en- 35
- gaging means in raised position, and a thread guide on the end of the latch and receiving the roving intermediate the rolls and the spinning mechanism. 40
19. In a machine of the class described and in combination with drawing rolls and spinning mechanism, means located adjacent the drawing rolls for severing the roving, a latch cooperating with said severing means and controlling the actuation thereof to engage the roving, and a guide mounted on the latch located intermediate the rolls and spinning mechanism for directing thread to the latter and adapted to co- 45 operate with said latch. 50
20. In combination with feeding and spinning mechanism and the like, a stop means for the roving, a latch associated therewith, and a combined thread guide and control 55 device for said stop means, said guide being mounted on said latch and located between the feeding and spinning mechanism.
21. In a spinning frame and in combination with the bobbin supports, drawing rolls 60 and spinning mechanism, a roving severing means for each set of drawing rolls comprising a roving engaging means pivoted to move in a substantially vertical plane into contact with the roving, a latch pivoted on 65 an axis substantially parallel to the axes of the rolls and beneath the latter, and a thread guide on the end of the latch and receiving the roving intermediate the rolls and the spinning mechanism.

JOHN P. GAREY.
